No. 674,408.

Patented May 21, 1901.

W. F. HARTIG.

CULTIVATOR.

(Application filed Nov. 21, 1900.)

(No Model.)

UNITED STATES PATENT OFFICE.

WILLIAM F. HARTIG, OF EVANSVILLE, INDIANA.

CULTIVATOR.

SPECIFICATION forming part of Letters Patent No. 674,408, dated May 21, 1901.

Application filed November 21, 1900. Serial No. 37,282. (No model.)

To all whom it may concern:

Be it known that I, WILLIAM F. HARTIG, a citizen of the United States, residing at Evansville, in the county of Vanderburg and State 5 of Indiana, have invented a new and useful Cultivator, of which the following is a specification.

My present invention relates to improvements in cultivators of that type which comprehend the employment of a diagonal cross-bar or standard-carrying plate bolted to the under side of the plow-beam and serving to support a series of plow-standards and shovels.

15 The invention is directed more particularly, however, to the improvement of the cross-bar, whereby the latter when applied to the plow-beam will be disposed with a slight longitudinal inclination from the horizontal to locate 20 the series of shovels in a similar inclined plane.

25 The invention is further directed to such construction of the cross-bar as will obviate the necessity for recessing or notching the plow-beam to accommodate the upper end of the center plow-standard and the nut mounted thereon, this recessing or notching of the beam being usually necessary and very objectionable, as the beam is thereby materially weak- 30 ened.

35 A still further object of the invention, subordinate, however, to those enumerated, is to stiffen the cross-bar to prevent distortion of the latter without materially increasing its weight.

To the attainment of these ends the invention consists in providing the cross-bar with a beam-seat disposed at an angle to the bar and having a lateral inclination which serves 40 to incline the bar longitudinally to permit the use of plow-standards of the same length, in elevating the beam-seat above the cross-bar to dispose the upper ends of the standards in a plane below the beam to obviate the notching of the latter, and in forming annular flanges or seats extending above and below the cross-bar concentric with the openings for the plow-standards and having their bearing-faces disposed in planes parallel with the 45 plane of the beam-seat to strengthen the cross-bar and to facilitate the retention of the standards in perpendicular positions in a

manner to be made apparent, the cross-bar being further strengthened by a surrounding flange extending both above and below the 55 same.

The invention resides in certain other features of construction and arrangement, all as will hereinafter be fully described, illustrated in the accompanying drawings, and defined 60 in the appended claims.

In said drawings, Figure 1 is a plan view of a cultivator constructed in accordance with my invention. Fig. 2 is a side elevation thereof. Fig. 3 is a plan view of the cross-bar detached. Fig. 4 is an end elevation thereof. Fig. 5 is a longitudinal section on the line 5 5 of Fig. 3. Fig. 6 is a transverse section on the line 6 6 of Fig. 3, and Fig. 7 is a bottom plan view of the cross-bar. 70

Referring to the numerals employed to designate corresponding parts throughout the views, 1 indicates a plow-beam of usual construction, 2 the handles, and 3 the support, bar, or cross-bar disposed below the beam at 75 an angle to the line of draft and employed for the attachment of any desired number (but preferably three) of plow-standards 4, carrying shovel-plows or other forms of blades 5. The cross-bar 3 is a comparatively light metal 80 casting comprising the cross-bar proper in the form of an elongated plate having a laterally-curved front end 6, connected at its extremity to the contiguous side of the cross-bar by a narrow web 7. The extremity of 85 the curved end 6 is given a decided rise to locate it and the web 7 in a plane above the bar to form an elevated or offset beam-seat 8, disposed diagonally from the front edge of the end 6 to the opposite side of the bar 3 at 90 a considerable distance from the front end of the latter. One side wall 9 of this elevation or offset is given a lateral inclination increasing in degree from the rear end of the beam-seat to its outer extremity. The bar 3, the 95 curved front arm thereof, and the web 7 are provided with a continuous depending flange 10, which is extended slightly above the upper face of the bar proper to insure such rigidity of the casting as will preclude the possibility of its twisting or buckling when subjected to excessive strains. 100

The upper surface or face of the offset beam-seat is made perfectly smooth and flat to bear

firmly against the under side of the plow-beam, and besides being longitudinally disposed in an angular direction with respect to the bar it is transversely inclined with respect 5 to the plane of the bar or plate, as shown in Fig. 4. The effect of this transverse inclination of the beam-seat will be to effect more or less elevation of the rear end of the cross-bar when the inclined face of the seat is disposed 10 directly against the horizontal under side of the plow-beam. Therefore, if a series of plow-standards of identical length are pendent from the bar the plows will be disposed in horizontally-inclined series, which is a necessary 15 arrangement in cultivators of this type and is ordinarily obtained by employing plow-standards of different lengths or by making special arrangement for endwise adjustment of the standards to secure proper relative 20 penetrations of the plows or shovels.

The elevated beam-seat is preferably cast hollow, as shown, and adjacent to its opposite ends the top wall thereof is provided with bolt-holes 11 and 12 for the reception of securing-bolts 13, passed through the plow-beam, the hole 12 being disposed in the plane of the longitudinal center of the bar 3.

We have now seen that by providing an elevated beam-seat which is both longitudinally 30 and transversely inclined with respect to the cross-bar the latter when attached to the plow-beam will be given such longitudinal inclination as is necessary to secure the desired relation of the shovels or plows. It will 35 be seen, however, that the attainment of this result is accompanied by slight transverse inclination of the cross-bar. Provision must therefore be made for permitting the plow-standards to assume true perpendicular positions, as shown in Fig. 2. This is accomplished by providing openings 14, 15, and 16 at the center of the bar and at the front and rear ends thereof, the opening 14 being disposed closely adjacent to the offset beam-seat, which latter is formed with a concavity 45 17, concentric therewith. These openings are designed for the reception of the threaded shanks 18 of the standards 4, and their axes are perpendicular to the plane of the beam-seat 50 or bearing-face—that is to say, the axes of these openings are not perpendicular to the plane of the cross bar or plate, but are in slight angular relation thereto in order that the standards may assume perpendicular positions with 55 respect to the horizontal under face of the plow-beam, and therefore positions perpendicular to the ground. This being true, it follows that provision must be made for properly abutting or seating the bearing-shoulders 19 60 of the standards, disposed below the bar, and the securing-nuts 20, screwed upon the shanks 18 above the bar. This I accomplish by casting upon the upper and under faces of the bar 3 a series of annular projections, flanges, 65 or seats 21 and 22, surrounding the openings and having their upper or under faces, as the case may be, disposed in planes parallel with

the plane of the beam-seat, so that the shoulders 19 may bear squarely against the seats 22, while the seats 21 facilitate in like manner 70 the even rigid abutment of the nuts 20 when screwed to place to secure the plow-standards in rigid relation with the bar.

When the bar is secured to the plow-beam, as in use, it will be disposed in diagonal relation thereto, as shown, and will be longitudinally inclined from the horizontal to dispose the shovels in a horizontally-inclined series; but the bar is disposed a sufficient distance below the plow-beam to permit the nut 80 20 of the intermediate standard to be disposed below the beam instead of being located within a cut-out portion thereof, as in cultivators of the usual construction.

It will therefore appear that I have produced a cross-bar for cultivators embodying a construction best calculated to effect the accomplishment of the various objects sought to be attained; but while the present construction illustrated and described is believed 90 at this time to be the preferable embodiment of the invention I do not wish to limit myself to the details of construction and contour enumerated, but reserve the right to effect such changes, modifications, and variations as may be clearly embraced within the scope of the protection prayed.

What I claim is—

1. A cultivator cross-bar provided with a beam-seat to which the cross-bar is relatively 100 inclined.
2. A cultivator cross-bar provided with an offset beam-seat.
3. A cultivator cross-bar provided with a beam-seat offset from its upper face.
4. A cultivator cross-bar provided with a relatively-inclined beam-seat offset therefrom.
5. A cultivator cross-bar provided with a beam-seat both longitudinally and laterally 110 inclined with respect to the bar.
6. A cultivator cross-bar provided with an offset beam-seat inclined both longitudinally and laterally with respect to the bar.
7. A cultivator cross-bar provided with an 115 offset, diagonally-disposed beam-seat.
8. A cultivator cross-bar having a laterally-extended end, and a laterally-inclined beam-seat extending diagonally from the extremity of said lateral end to the body of the bar.
9. A cultivator cross-bar having a laterally-curved end, and a beam-seat having diagonal 125 relation to the bar and extending from the body thereof to the extremity of the laterally-extended end, said seat being offset from the upper face of the bar.
10. A cultivator-bar provided with a laterally-extended end and having a transversely-inclined beam-seat offset from the upper face of the bar and disposed diagonally across the 130 bar and terminating at the extremity of the laterally-extended end.
11. A cultivator cross-bar provided with a beam-seat offset from its upper face and in-

clined with respect thereto, and a series of openings formed in the bar and having their axes disposed perpendicular to the inclined beam-seat.

5 12. A cultivator cross-bar having a beam-seat inclined with respect to the face thereof, a series of openings formed in the cross-bar and having their axes disposed perpendicular to the seat, and annular seats surrounding said openings and having their bearing-faces disposed in a plane or planes parallel with the inclined beam-seat.

10 13. A cultivator cross-bar having a beam-seat offset therefrom and inclined with respect to the face thereof, a series of openings formed in the cross-bar and having their axes disposed perpendicular to the seat, and annular seats surrounding said openings and having their bearing-faces disposed in a plane 20 or planes parallel with the inclined beam-seat.

15 14. A cultivator cross-bar comprising a plate having flanges at its edges extended above and below the plate, and a series of 25 annular seats extending from the plate between the flanges.

20 15. The combination with a beam, of means for supporting a plurality of plows arranged in a series disposed transversely to the beam, 30 said plows being disposed at different distances below the beam and having standards of the same length.

35 16. A cultivator comprising a beam and a cross-bar, one of said elements being provided with a rigid inclined seat against which the

other of said elements is secured to hold the cross-bar in endwise-tilted relation to the beam.

17. A cultivator comprising a beam and a cross-bar, one of said elements being provided 40 with an integral inclined seat against which the other of said elements is secured to dispose the cross-bar in longitudinally-inclined relation to the beam.

18. In a cultivator, the combination with 45 the beam and a cultivator cross-bar, of a rigid, offset, inclined seat upon one of said elements, against which seat the other element is secured to dispose the cross-bar in endwise-tilting relation to the beam. 50

19. The combination with a plow-beam, of an endwise-tilted support carried thereby, a rigid inclined beam-seat upon one of said elements, against which seat the other of said elements is secured, a plurality of plow-stands 55 of equal length carried by the cross-bar, and a plow carried by each standard.

20. The combination with a beam, of an endwise-tilted cross-bar diagonally disposed with respect to the beam, one of said elements 60 being provided with an inclined seat against which the other of said elements is secured.

In testimony that I claim the foregoing as my own I have hereto affixed my signature in the presence of two witnesses.
